UNITED STATES PATENT OFFICE.

JOHN W. HASBURG, OF CHICAGO, ILLINOIS.

PAINT-PACKAGE.

1,049,711.

Specification of Letters Patent.

Patented Jan. 7, 1913.

Application filed April 12, 1912. Serial No. 690,372.

To all whom it may concern:

Be it known that I, JOHN W. HASBURG, a citizen of the United States, residing at Chicago, in the county of Cook and State of Illinois, have invented certain new and useful Improvements in Paint-Packages, of which the following is a specification.

My invention relates to improvements in paint packages, and has especial reference 10 to packages designed to contain gold paint for ceramic decoration. Paint of this character is of a mastic nature and in its preparation for use it is usually deposited upon a glass palette and inclosed by a substantially transparent cover, such as a sheet of celluloid, or the like, overlying the palette and then substantially hermetically sealed in the package to exclude dust and other objectionable matter. The paint deposit is 20 variably of a dark brown or chocolate color, as it appears to the purchaser, but when applied and after the article to which the paint has been so applied has been burned or fired, it changes color materially, having the metallic color and appearance of gold, such as, 25 known in the art as Roman; green; white; and ruby gold, or green; red; brown; gray and verdigris bronze.

The only means that the purchaser has 30 heretofore had for determining the resultant color or character of gold resulting from the use of a deposit in a given package is the statement of the manufacturer upon the package. To contemplative purchasers, unfamiliar with the various colors and characteristics of the product of several manufacturers, the mere statement of color is not 35 always satisfactory. I therefore find that an ocular demonstration of these features of 40 the product, accompanying the package, affords a ready means for determining the results that may be expected from the use of the paint after it has been applied to an article, for decorative purposes and said article 45 has been put through the usual process of firing. With these objects in view I provide a surface, in connection with the usual brown deposit of paint, which has been previously prepared to simulate the color of the product 50 in its finished state.

In the drawing; Figure 1 is a cross section of a typical gold paint package as it appears in a box for shipment. Fig. 2 is a plan view of same with the top removed.

In both views the same reference characters indicate similar parts.

5 is the usual glass palette with the brown colored gold paint deposit 6 near its middle zone, inclosed by a substantially transparent celluloid cover 7, that is preferably sealed 60 to the palette, as at 8, in any desirable manner, to render the package substantially air and dust tight. This constitutes the usual package, as heretofore prepared for the market. For shipment it may be placed in a 65 box 9 having a suitable lid or closure 10.

My invention consists in preparing a surface, associated with the package, which has previously been prepared to simulate the color of the paint, as it will appear after application to and firing of the article to which it has been applied.

In the specific embodiment illustrated, 11 is a sheet of paper having its uppermost surface prepared, by suitable means, to simulate the color and appearance of the accompanying paint after application to, and completion of, ceramic articles to which it may be applied. The paper may be pasted to the back of the glass palette 5, or to the 80 bottom of the containing box 9, or the respective surfaces of the palette, or the box may be directly treated to produce the desired effect. It is preferable to present such prepared surface so that it may become visible from the front or through the opening in the containing box 9, so that it may be inspected through the substantially transparent palette and cover and without removing the package from the box, but my invention 85 is not limited to such an arrangement and in this respect it is susceptible to a number of variations and modifications.

Having described my invention, what I claim is:

A ceramic gold paint package, comprising, 95 a receptacle having bottom member, and a substantially transparent top member hermetically sealed thereto, a transparent palette, a deposit of ceramic gold paint smaller 100

than the palette, carried by the top surface of the palette, and an imitative surface prepared to simulate that changed appearance which the gold paint will assume after baking, said surface underlying the palette and visible through the palette and cover, as a border around the gold deposit, and the palette, paint and surface being contained

within the receptacle and thereby protected against exterior influences.

10

In testimony whereof I hereunto set my hand in the presence of two witnesses.

JOHN W. HASBURG.

In the presence of—

W. LINN ALLEN,

MARY F. ALLEN.
